The United States of America.

To all whom these Letters Patent shall reach.

William

the United States, hath alleged that he has invented a new and useful improvement which improvement he states has not been known and before his application, has that he does hereby believe that he is the true inventor or discoverer of the said improvement, hath paid into the treasury of the United States the sum of three dollars, delivered a copy of the same, and presented a petition to the Secretary of State, signifying a desire of obtaining an exclusive property in the said improvement, and praying that a patent may be granted for that purpose. Wherefore I do therefore so grant, according to law, to the said his heirs, administrators or assigns for the term of fourteen years, from the day of one thousand eight hundred and the full and exclusive right and liberty of making, constructing, using and vending or otherwise dealing in, the said improvement, a description whereof is given in the words of the said himself, in the schedule hereinafter, and is made a part of these presents.

In testimony whereof, I have caused these Letters to be made Patent, and the Seal of the United States to be hereunto affixed.

At the City of Washington, this day of in the year of our Lord one thousand eight hundred and and of the independence of the United States of America.
Be it so ordered.

James Monroe

BY THE PRESIDENT.

John Quincy Adams
Secretary of State.

City of Washington, To wit:

I DO HEREBY CERTIFY, That the foregoing Letters Patent were delivered to me on the day of in the year of our Lord one thousand eight hundred and to be executed and I have examined the same, and find them understandable in law, and I do hereby witness the same to be the genuine of Alice, whom I often do see on the date aforesaid, to wit on the day of in the year aforesaid.

Secretary General of the United States.
